RAZOR

Victor Merlo, Elizabeth, N. J.

Application July 7, 1938, Serial No. 218,001

2 Claims. (Cl. 30—336)

This invention relates to certain new and useful improvements in razors.

The primary object of the invention is to provide a razor of the so-called straight razor type as distinguished from the usual safety razor and comprises a holder for a removable relatively long blade with a handle pivotally connected to one end of the holder and openable and closable in the usual manner relative to the blade and holder.

A further object of the invention is to provide a razor of the foregoing character wherein the holder that is substantially U-shaped in cross-section and possessing a limited degree of resiliency is designed for the removable support of a double edged blade that carries a longitudinally extending rib on each side face thereof intermediate the cutting edges of the blade and with which ribs, the side walls of the holder are resiliently engaged for retaining the blade in position in the holder, the side walls of the holder being fashioned to accommodate the mounting of the ribs on the blade and with portions of said walls only lightly engaged with the blade at opposite sides of the ribs.

It is a further object of the invention to provide a razor of the foregoing character wherein in the outer ends of the side walls of the holder are cut away with the outer end of the removable blade exposed by the cut away portion and provided with a finger grip to facilitate removal of the blade from the holder.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a side elevational view of a razor constructed in accordance with the present invention;

Figure 2 is a vertical longitudinal sectional view, partly broken away of the holder for the blade of the razor, with the razor blade in position in the holder;

Figure 3 is an edge elevational view of the blade having a longitudinally extending rib at each side with the ribs at each side notched adjacent each end to provide a finger grip;

Figure 4 is a cross-sectional view taken on line 4—4 of Figure 1, showing the side ribs attached to the razor blade with the ribs engaged by side portions or walls of the holder;

Figure 5 is a cross-sectional view similar to

Figure 4, with the razor blade removed from the holder; and

Figure 6 is a cross-sectional view of another form of blade wherein the side ribs form an integral part of the blade.

The razor is of the usual straight-edge type and comprises a back or holder designated in general by the reference character 10 having the usual shank 11 at one end thereof to which the handle 12 is pivotally attached as at 13. The 10 holder 10 as shown in Figures 4 and 5 is of general U-shape in cross-section and includes a pair of side walls designated in general by the reference character 14, providing a top loop or rolled portion 15, the side walls 14 being bent or 15 curved inwardly as at 16 adjacent the upper looped edge 15, then bent outwardly and downwardly to provide straight or flat side wall portions 17 and thereafter arched inwardly at their lower ends as at 18. The inwardly curved portions 16 of the side walls 14 and the inwardly curved lower edges 18 of said side walls provide 20 razor blade engaging surfaces 16a and 18a respectively.

The holder 10 removably receives a double edged razor blade 19 having cutting edges 20 and said blade 19 at each side thereof intermediate the cutting edges 20 and secured thereto in any preferred manner as indicated in Figure 4 a longitudinally extending rib 21 and said ribs 30 adjacent each end thereof are provided with a finger notch 22 to facilitate placement of the blade 19 in the holder 10 and as shown in Figures 1 and 2, the outer ends of the side walls 14 of the holder 10 are arcuately cut away as at 23 to provide a clearance for the exposure of the finger notches 22 at the outer end of the blade 19 when the blade is completely received in the holder 10 as shown in Figures 1 and 2 to facilitate removal of the razor blade from the 40 holder 10.

With the razor blade positioned in the holder as illustrated in Figures 1, 2 and 4, the flat or straight side wall portions 17 of the holder 10 frictionally engage the ribs 21 for retaining the blade in the holder, the portions 16a and 18a slightly engaging the opposite sides of the blade 19 to steady the blade in the holder, one cutting edge 20 of the blade projecting outwardly of the ends 18 of the holder as illustrated. The flat 45 wall portions 17 of the side walls 14 flattens the skin of the face to a taut condition so that the cutting edge 20 of the blade moves smoothly over the face during shaving. The blade and holder may be easily sterilized to answer sani- 50 55

tary requirements and the blade may be stropped while held in the holder, the blade being reversible to present either cutting edge thereof for use.

A modification of the blade 19 is shown in Figure 6, the blade 19a shown in Figure 6, having the side ribs 21a forming an integral part thereof, the ribs 21a in effect being in the form of an elongated rectangular block with blade portions 19a projecting from diametrically opposite sides thereof and intermediate the other edges or side faces of the block.

From the above detailed description of the invention, it is believed that the construction and operation thereof will at once be apparent, and while there are herein shown and described the preferred embodiments of the invention, it is nevertheless to be understood that minor changes may be made therein without departing from the spirit and scope of the invention as claimed.

I claim:

1. In a razor of the character described, a resilient blade holder having a handle hinged to one end thereof, said holder being of substantially U-shape in cross section providing side walls, a longitudinally extending outwardly off-

set portion carried by each side wall between the longitudinal side edges thereof, a double edged razor blade removably positioned in the holder with the walls of the holder frictionally engaged therewith and a reinforcing rib on each side of the blade engaged by the walls of the offset portions of the holder.

2. In a razor of the character described, a resilient blade holder having a handle hinged to one end thereof, said holder being of substantially U-shape in cross section providing side walls, a longitudinally extending outwardly offset portion carried by each side wall between the longitudinal side edges thereof of a double edged razor blade removably positioned in the holder with the walls of the holder frictionally engaged therewith and a reinforcing rib on each side of the blade engaged by the walls of the offset portions of the holder, the outer ends of the side walls of the holder being cut away and each rib having a finger notch therein adjacent each end with the outer end finger notches positioned in the cut away portions of the side walls to facilitate removal of the blade from the holder.

VICTOR MERLO. 25
